BY J. R. Littell,
his ATTORNEY.

UNITED STATES PATENT OFFICE.

ERASTUS A. WARE, OF NOANK, CONNECTICUT, ASSIGNOR OF ONE-HALF
TO MICHAEL B. McDONALD, OF NOANK, CONNECTICUT.

PIPE-WRENCH.

SPECIFICATION forming part of Letters Patent No. 709,064, dated September 16, 1902.

Application filed June 12, 1901. Serial No. 64,252. (No model.)

To all whom it may concern:

Be it known that I, ERASTUS A. WARE, a citizen of the United States, residing at Noank, in the county of New London and State of Connecticut, have invented certain new and useful Improvements in Pipe-Wrenches, of which the following is a specification.

This invention relates to pipe-wrenches; and it has for its object to provide an improved device of this class which will be superior in point of facility of adaptation to pipes or other work of varying dimensions and which will be positive in operation, inexpensive in construction, and generally superior in point of efficiency and serviceability.

In the drawings, Figure 1 is a side view of a pipe-wrench constructed according to my invention. Fig. 2 is a transverse sectional view of the same, taken upon the line *x x*, Fig. 1. Fig. 3 is a front edge view of the wrench.

Corresponding parts in all the figures are denoted by the same reference characters.

Referring to the drawings, 1 designates my improved wrench, which comprises a body portion or shank 2, provided at one end with a fixed jaw 3 and at the other end with a handle portion 4 and a rotary jaw 5, arranged intermediate of the handle portion and the fixed jaw. The rotary jaw 5 is adapted to occupy a fixed operative position, but embodies a cam-shaped operative edge portion or periphery 6, between which and the curved inner operative face 7 of the fixed jaw 3 the pipe is gripped. In the preferred form of construction the rotary jaw 5 is mounted upon a transverse bearing-pin 8, which passes through the shank or body portion 2, which consists of two parallel side pieces 9, between which the rotary jaw 5 is arranged. In forming the rotary jaw 5 a flat plate 10 of suitable metal is provided, and the edge portion of periphery 6 of said plate is so curved, beginning at a predetermined point, as at 11, that each successive portion of the periphery 6 is farther from the point through which the bearing-pin 8 passes, continuing to a point, as at 12, approximately in line with the point 11 and the point through which the bearing-pin 8 passes. The points 11 and 12 of the per-

iphery 6 are merged together in a curved shoulder 13, which constitutes an inoperative portion of the periphery 6.

It is manifest from the above that as the rotary jaw 5 is rotated in the direction denoted by the arrow in Fig. 1 the space between the jaws 3 and 5 will be gradually diminished up to a point in the rotation of the jaw 5 at which the point 12 of the periphery 6 is in the closest possible proximity to the jaw 3.

The side pieces 9 of the shank or body portion 2 may be provided with a plurality of perforations 14, arranged in longitudinal series to receive the bearing-pin 8 in any desired position with respect to the fixed jaw 3, and thus regulate the working relation between the jaws 3 and 5.

The operation and advantages of my improved pipe-wrench will be readily understood. The device is manipulated in the customary manner; but in fitting the wrench to the work the fixed jaw 3 is first brought to bear upon the same, and the rotary jaw 5 is then turned until its periphery 6 bears operatively upon the work. The handle portion 4 is then operated in the customary manner, and the operative surfaces 7 and 6 of the jaws 3 and 5 respectively grip the work positively and cause its rotation, said operative surfaces being preferably toothed or transversely serrated in the customary manner. The operative surfaces of the jaws 3 and 5 may thus be relatively gaged or adjusted to fit the varying dimensions of work by merely rotating the jaw 5—an operation both simple and saving of time and inconvenience. The rotary jaw 5 may be adjusted bodily along the body portion or shank 2 by shifting the bearing-pin 8 along the series of perforations 14, formed in the side pieces 9. The cam-shaped rotary jaw may thus adapt the wrench to all diameters of work customarily met with. It is manifest that the wrench may also be satisfactorily applied to other classes of work than those described, in which its method of use will be substantially the same.

I do not desire to be understood as limiting myself to the details of construction and arrangement as herein described and illustrated,

as it is manifest that variations and modifications may be made in the features of construction and arrangement in the adaptation of the device to various conditions of use 5 without departing from the spirit and scope of my invention and improvements. I therefore reserve the right to all such variation and modification as properly fall within the scope of my invention and the terms of the 10 following claims.

Having thus described my invention, I claim and desire to secure by Letters Patent—

1. A device of the class described, comprising a body portion provided at one end with a handle and adjacent to the other end with a transverse curved recess the outer portion of which forms a hooked serrated jaw and intermediate such handle and jaw with a slot 15 extending through said body portion in the plane of such recess, and a rotary jaw eccentrically mounted in such slot and provided with a serrated periphery which is so curved from a predetermined point that it constantly 20 recedes from the bearing-pin until a point is 25 reached approximately in line with the starting-point and the bearing-pin, the periphery

between the initial and terminal points forming an inwardly-curved smooth shoulder.

2. A device of the class described, comprising a body portion embodying two parallel side pieces provided near one end with a transverse recess on one side the outer end portion of which forms a hooked serrated jaw and at the other end secured to a portion inserted between such side pieces to form a handle, and a rotary jaw eccentrically mounted between such side pieces intermediate the hooked jaw and the handle, and provided with a serrated periphery which is so curved from a predetermined point that it constantly recedes from the bearing-pin until a point is reached approximately in line with the starting-point and the bearing-pin, the periphery 35 between the initial and terminal points forming an inwardly-curved smooth shoulder. 40

In testimony whereof I have signed my name in the presence of the subscribing witnesses.

ERASTUS A. WARE.
